UNITED STATES PATENT OFFICE.

JOSEPH H. TRAVIS, OF CHARLESTOWN, MASSACHUSETTS.

DESIGN FOR CHAIR-FRAMES.

Specification forming part of Design No. 6,834, dated September 2, 1873; application filed May 23, 1873.
[Term of Patent 3½ years.]

To all whom it may concern:

Be it known that I, JOSEPH H. TRAVIS, of Charlestown, in the county of Middlesex and State of Massachusetts, have invented a new and useful Design for a Chair-Frame, which, by the accompanying plate of drawings, is fully illustrated and herein fully described, reference being had to said plate of drawings.

The improved design embraced herein is upon the frame of reclining-chairs, and more particularly to that class of such chairs as are constructed under the several Letters Patent issued to me.

In the accompanying plate of drawings is a side elevation of one side frame of a chair, which side frame is designed according to this invention, and corresponding thereto in the construction of the chair there is another side frame, which, as ordinarily, are suitably joined together and braced.

In the drawings, A is the front leg; B, the rear leg; C, the seat; D, the back; and E, the arm rest or support, the whole making a side frame of a chair of the class stated. The front leg A is of the lower end of the vertically backward inclining round bar a, and the rear leg B is of the lower end of a similar round bar, b, vertically forward inclining, and

at a right angle, or nearly so, to the length of the bar a, the plane or direction of both intersecting each other. The seat C is of a curved rail, c, which has its concave edge d uppermost, and is extended to the rear of the front leg-bar a, and thence in an upwardly-curving line, f, making the back D; it meets the leg-bar a at or near its upper end, as shown. The arm rest or support E is of the upper end of a curved rail, g, which extends to the rear of the front leg-bar a, and by a bar, l, round in shape, passes downward into a line or direction parallel to and back of the leg-bar a, to which, as well as to the rear leg-bar b, it is connected, and the whole as shown in the drawings. m, drops or tips, of ornamental shape, applied at the ends of the various parts of the side frame, as shown; H, a post, made of ornamental outline, and rising from the seat-rail c, as herein shown.

Having thus described my improved design, what I claim is as follows:

The design for a chair-frame, substantially as herein shown and described.

J. H. TRAVIS.
